UNITED STATES PATENT OFFICE.

THOMAS COKE JONES, OF WILLOWS, CALIFORNIA.

CAR-COUPING.

SPECIFICATION forming part of Letters Patent No. 293,579, dated February 12, 1884.

Application filed June 15, 1883. (No model.)

To all whom it may concern:

Be it known that I, THOMAS COKE JONES, of Willows, in the county of Colusa and State of California, have invented a new and useful Improvement in Car-Couplings, of which the following is a full, clear, and exact description.

Reference is to be had to the accompanying drawings, forming a part of this specification, in which similar letters of reference indicate corresponding parts in all the figures.

Figure 1 is a plan view of my improvement, one of the draw-heads being shown in section. Fig. 2 is a sectional side elevation of one part of the same, taken through the line *xx*, Fig. 1. Fig. 3 is a front elevation of one part of the same. Fig. 4 is a sectional end elevation of a part of the same. Fig. 5 is a side elevation of the foot-lever and its connections. Fig. 6 is a side elevation of the catch-bar and keeper, the lever being shown in section.

The object of this invention is to facilitate the coupling and uncoupling of cars, and promote convenience and security in the use of such couplings.

The invention consists in a car-coupling constructed with a draw-head having a **U**-shaped draw-bar connected with the draw-rod, with which is also connected a coupling-hook held down by a spring and a bow and yoke. With the coupling-hook is connected a lifting-bar, a lever provided with a keeper and catch-bar, and an upright bar and its keeper, whereby the cars can be uncoupled from the side of the track or the top of a car. With the upright bar is connected a foot-lever, so that the brakeman can uncouple the cars from the top of a car, as will be herein-after fully described.

A represents the draw-beams attached to the car-frame, and which are connected at their forward ends by cross-bars B to form a seat for the draw-head C. The draw-head C is cast upon the ends of a **U**-shaped draw-bar, D, through the bend of which passes the draw-rod E. The draw-rod E is connected with the draw-beams A by sliding cross-bars F, supporting slides G, and springs H in the ordinary manner. The draw-rod E is kept in place by a key, I, or other suitable fastening at its rear end, and has a head formed upon

its forward end, which enters a recess in the rear end of the coupling-hook J, and is secured in place by a bolt, K, passing through the said head, the rear end of the coupling-hook J, and through the arms of the draw-bar D. With this construction the coupling-hook J can be detached by taking out the bolt K, so that the car can be coupled by an ordinary link and pin, the draw-head having a vertical hole formed through it to receive the said pin. The coupling-hook J extends forward through the interior of the draw-head C, and its forward end is inclined or beveled, so that it will be raised by the entering end of the coupling-link L. The coupling-hook J is held in gear with the link L by its own weight, and by the pressure of the arched spring M, the rear end of which is bent around or is otherwise connected with the rear end of the said coupling-hook J. The forward end of the spring M rests upon the upper side of the forward part of the coupling-hook J.

Around the spring M and the coupling-hook J is passed a bow, N, the bend of which rests upon the middle part of the said spring M, and its ends pass through the yoke O and have nuts P screwed upon them. The ends of the yoke O project so as to rest against the lower side of the draw-bar D, so that the tension of the spring M can be regulated to hold the coupling-hook J down with any desired pressure by adjusting the nut P.

Q is a bar, the middle part of which is bent into **U** shape, and its end parts are bent outward, downward, and inward, so as to pass around the spring M and coupling-hook J loosely, without interfering with the movements of the said spring and hook. The arms of the bar Q are held from spreading, and thus coming off the coupling-hook J, by a bolt, R, passing through the said arms. The upper or bent part of the bar Q is pivoted by a bolt, S, or other suitable means to a lever, T, one end of which is pivoted to a bracket, U, or other support attached to the end of the car V. With this construction, by operating the lever T, the coupling-hook J can be raised to uncouple the cars. The lever T is kept in place by a keeper, W, attached to the end of the car, and is supported, while holding the coupling-hook raised, by a catch-bar, X, also attached

to the said end of the car. The free end of the lever T projects nearly to the side of the car, as shown in Figs. 1 and 3, so that the said lever can be operated from the side of the track 5 to uncouple the cars, and to lower the coupling-hook J into a coupling position.

To the lever T, at a little distance from its free end, is hinged the lower end of a bar, Y, which passes up through a keeper, Z, attached 10 to the upper part of the end of the car, and has a handle, a, formed upon or attached to its upper end for convenience in operating it. With this construction the cars can be uncoupled from the top of a car by raising the bar Y, and pushing its upper end outward to cause the lever T to engage with the catch-bar X. The coupling-hook J can be lowered 15 into a coupling position by drawing the upper end of the bar Y to the rearward, to disengage the lever T from the catch-bar X. The part 20 of the bar Y that projects above the top of the car V is slotted to receive the end of the lever b, which is pivoted to a support, c, attached to the top of the car. The free end of the lever b projects into such a position that it can 25 be readily operated by the brakeman with his feet, in case his hands should be engaged with the brake or otherwise.

I do not abandon or dedicate to the public 30 any patentable feature set forth herein, and not hereinafter claimed, but reserve the right to claim the same, either in the reissue of any patent that may be granted upon this appli-

cation, or in other applications for Letters Patent that I may make.

35

Having thus fully described my invention, I claim as new and desire to secure by Letters Patent—

1. A car-coupling constructed substantially as herein shown and described, and consisting 40 of the draw-head A, the U-shaped draw-bar D, the spring-pressed coupling-hook J, the bow and yoke N O, and a mechanism for raising the coupling-hook, as set forth.

2. In a car-coupling, the combination, with 45 the draw-head A, the U-shaped draw-bar D, the spring coupling-hook J, the bow N, and yoke O, of the lifting-bar Q, the lever T, the catch-bar X, and the bar Y, substantially as shown and described.

50

3. In a car-coupling, the combination, with the draw-head A, and the U-shaped draw-bar D, of the coupling-hook J, provided with a recess at its rear end, spring M, bow N, yoke O, draw-rod E, cross-bars F, slides G, and spring H, substantially as shown and described.

4. In a car-coupling, the combination, with the draw-head A, the U-shaped draw-bar D, the coupling-hook J, the bow N, and yoke O, of the lifting-lever Q, the lever T, the catch-bar 60 X, keeper W, slotted bar Y, and foot-lever b, substantially as shown and described.

THOMAS COKE JONES.
